UNITED STATES PATENT OFFICE.

JOHN G. MUELLER, OF DAYTON, OHIO.

RAIL-BRACE.

1,353,412.

Specification of Letters Patent. Patented Sept. 21, 1920.

Application filed November 1, 1918. Serial No. 260,648.

To all whom it may concern:

Be it known that I, JOHN G. MUELLER, a citizen of the United States, residing at Dayton, in the county of Montgomery and State of Ohio, have invented certain new and useful Improvements in Rail-Braces, of which the following is a specification, reference being had therein to the accompanying drawing.

10 This invention relates to rail braces.

An object of the invention is to provide a rail brace which can be readily adjusted to position the rails to the desired gage and to positively retain them in fixed lateral relation with each other.

15 It is also an object of the invention to provide a brace adapted to be applied at the rail joints in connection with the fish-plates to prevent spreading of the rails at the joints and otherwise to strengthen the joint construction.

20 It is also an object of the invention to provide a standard rail brace and clamp equally adaptable to the different weights 25 in steel rails, and the variation of dimensions in rail joint construction, or, where the device is used for purposes other than a rail clamp and brace, that it may be readily adapted to variable dimensions of the parts 30 to be engaged thereby.

35 In the drawings, Figure 1 is a side elevation of my invention illustrating the brace as applied to the opposite rails of a track; and Fig. 2 is a longitudinal section of one set of the rail clamps shown in Fig. 1.

40 Referring to the drawings, I have shown the usual track arrangement of two parallel rails 1 and 2 with the rail brace applied thereto. 3 is a tie rod extending between and underneath the rails and projecting beyond the rails outside thereof. The ends of the rod are screw-threaded, as at 4, to a point well inside the rails to permit of 45 applying clamping members 5 on both sides of the base flange of each rail.

50 Coacting with the clamping member 5 is an angular shaped binding block 6 having an upwardly extending portion 7 and a flat portion 8 adapted to contact, respectively, with the edge of the rail flange and the bottom of the rail when the clamp is in position.

55 The binding block 6 and clamping member 5 are further provided with inclined bearing faces 9 and 10, respectively, con-

tacting one with the other, whereby both members of the clamp are simultaneously adjusted, the inclined faces being provided with tongue and groove connection to prevent relative lateral movement.

The members 5 and 6 are each provided with apertures 11 and 12, respectively, of a size suitable to freely receive the tie rod 3. The aperture 11 in the member 5 is elongated vertically to provide for adjustment of the members 5 and 6 to adapt the clamp to different weight rails. It will be understood, therefore, that the rail brace and the clamp used in connection therewith may be made in a standard size equally adaptable to all sizes or weights of rails, or, where the braces are used in connection with structures other than track construction the clamps are adaptable to a considerable variation of dimensions of the parts to be clamped.

55 The relation of the members 5 and 6 when assembled on the tie rod and applied to the rails by reason of the coacting angular surfaces 9 and 10 is that of the binding wedge and clamp in their effect upon the flange of the rail, the flange being positively gripped on the two sides and edge thereof when the clamp is drawn to position on the tie rod.

60 Two sets of the clamping devices are usually employed with each tie rod, two for each rail, but it is obvious, of course, that a greater or less number may be employed to meet the requirements of different forms of track construction.

65 To apply the brace to two opposite rails lock nuts 13 are first run on the threaded portions of the tie rod. The inner sets of 70 the clamping devices are then slipped over the rod and loosely adjusted thereon to the inner flange of the rail. The outer sets of 75 clamping devices are then placed on the rod and adjusted to the outer flanges of the 80 rails by lock nuts 14. By drawing on the nuts 14 the rails may be adjusted laterally 85 inwardly to required gage. The nuts 13 are then adjusted until the rails are securely bound, respectively, by the clamps and are 90 positively held against lateral movement in either direction by the combined action of the clamps and tie rod.

95 A locking member 15 is used in connection with the nuts 13 and 14 to prevent accidental displacement thereof. The locking device is made of bendable steel and com-

prises projections 16 and 17 adapted to be bent in opposite directions, the portion 17 being bent toward the adjacent nuts across two opposite faces thereof and the portion 5 16 toward the adjacent clamp 5 with the edges thereof projecting into notches 18 of the clamp. Thus, the nuts are positively locked against retraction and the clamps and tie rod are retained in fixed relation 10 with the rails against all possibility of accidental displacement.

It is obvious, of course, that my improved rail brace is also effective when applied to the rails as an anti-rail creeping device. 15 When used for the double purpose of bracing the rails laterally and also to prevent creeping of the rails longitudinally a number of the braces, at least two, are applied to each length of a rail and butted against 20 opposite sides of the ties to prevent lateral movement of each brace in one direction, except as the tie itself may move laterally. To make the clamps more effective to grip the rail flange the gripping surface of the 25 clamp members 5 and 6 may be toothed, as at 19 and 20, the teeth extending longitudinally of the gripping surface.

While I have shown the preferred form 30 of construction of my invention, it is obvious, of course, that modifications may be made thereof without departing from the principle of construction and application.

Having thus fully described my invention, what I claim as new and desire to secure by Letters Patent, is:—

1. In a rail brace, the combination, with a tie rod, of clamping devices disposed on opposite sides of the rail each device comprising a clamping member, and a binding 40 member, said members being adapted to engage, respectively, the top and bottom of the rail flange, and means whereby the opposite devices may be adjusted relative to the tie rod to clamp the opposite flanges of 45 said rail.

2. In a rail brace, the combination, with a tie rod, of clamping devices disposed on opposite sides of the rail, axially movable upon the tie rod each device comprising a 50 clamping member and a binding member, said members being adapted to engage the top and bottom, respectively, of the rail flange, and means whereby the opposite devices may be adjusted relative to the tie rod and toward each other to clamp the opposite flanges of said rail.

3. In a rail brace, the combination, with a tie rod, of a clamping device operable therewith adjacent each rail flange and comprising a clamping member, a binding member, said members being adapted to engage the top and bottom sides respectively of the rail flange and means whereby said members may be adjusted relative to the tie rod

and to each other to clamp a portion of said rail.

4. In a rail brace, the combination, with a tie rod, of a clamping device movable on the tie rod adjacent each rail flange and comprising a clamping member, a binding 70 member, said members being adapted to engage the top and bottom sides, respectively of the rail flange and means whereby said members may be adjusted axially of the tie rod and relative to each other to clamp a 75 portion of said rail.

5. In a rail brace, the combination, with a tie rod, of a clamping device operable therewith and comprising a clamping member and a binding member adjacent each rail 80 flange, said members being adapted to engage the top and bottom sides, respectively of the rail flange, means whereby said members may be adjusted relative to the tie rod and to each other to clamp a portion of said 85 rail; and means to positively interlock the adjusting means with one of said members.

6. In a rail brace, the combination, with a tie rod, of a plurality of sets of clamping devices disposed on opposite sides of two 90 opposite rails and comprising, respectively, a clamping member, a binding member, said members being adapted to engage the top and bottom sides, respectively of the rail flange and means whereby the clamping devices may be adjusted relatively to the tie 95 rod and to each other whereby a portion of each rail will be positively clamped by the device adjacent thereto and the opposite rails will be braced to prevent lateral movement thereof.

7. In a rail brace, the combination, with a tie rod, of a plurality of sets of clamping devices disposed on the opposite sides of two opposite rails and comprising, respectively, a clamping member, a binding member, said members being adapted to engage opposite sides of the rail flange, means whereby the clamping devices may be adjusted respectively relatively to the tie rod 105 and to each other, whereby the respective rails will be clamped between said devices and may be moved laterally to a predetermined position.

8. In a rail brace, the combination, with a tie rod, of clamping members adjacent each rail flange having an angular tongue and groove connection therebetween, and means to adjust said members relative to the tie rod and to each other, whereby a 110 portion of the rail will be clamped between said members.

9. In a rail brace, the combination, with a tie rod, of an adjusting device on the tie rod adjacent each rail flange comprising a 115 clamping member and a binding member having a tongue and groove connection therebetween, and means to adjust said mem-

bers simultaneously relative to each other and the tie rod whereby the binding member will be forced inwardly to engage the bottom of the rail flange and the clamping member will be forced upwardly and inwardly to engage the top of the rail flange whereby to clamp the flange between said members.

10. In a rail brace, the combination, with a tie rod, of a clamping member movable on the tie rod having an angular portion and a portion adapted to engage the top side of the rail flange, a binding member movable upon the tie rod and having an angular portion coacting with the angular portion of the clamping member, a flat portion adapted to engage the bottom side of the rail flange, and an upwardly extending projection adapted to engage the edge of the rail flange, and means to adjust said members, whereby the rail flange will be clamped on the two sides and edge thereof.
11. In a rail brace, the combination, with a tie rod, of a clamping member movable on the tie rod having an angular portion and a portion adapted to engage the top side of the rail flange, a binding member movable upon the tie rod and having an angular por-

tion coacting with the angular portion of the clamping member, a flat portion adapted to engage the bottom side of the rail flange, and means to adjust said members whereby the rail flange will be clamped on two sides thereof.

12. In a rail brace, the combination, with a clamping member having a portion adapted to engage the top side of a rail flange of variable dimensions and having a vertically elongated aperture therein, of a second apertured clamping member adapted to engage the bottom and edge of said flange, a tie rod extending through said aperture, and means to adjust said members on the tie rod whereby the two sides and edge of said flange will be clamped.

13. In a rail brace, the combination, with a tie rod, of a clamping device operable thereon adjacent each rail flange and comprising toothed clamping and binding members, and means whereby said members may be adjusted relative to the tie rod and to each other whereby the rail flange will be clamped between the teeth of said members.

In testimony whereof I affix my signature.

JOHN G. MUELLER.
